(57) **CLAIM**

I claim the ornamental design for a tent, as shown and described.

DESCRIPTION

FIG. 1 is a front perspective view of a tent of my new design in a first configuration;

FIG. 2 is a rear perspective view thereof;

FIG. 3 is a top perspective view thereof;

FIG. 4 is a right side perspective view thereof;

FIG. 5 is another right side perspective view thereof;

FIG. 6 is a left side perspective view thereof;

FIG. 7 is a front perspective view of the tent of FIG. 1 in a second configuration;

FIG. 8 is a right side perspective view thereof; and,

FIG. 9 is another right side perspective view thereof.

The dashed lines depict portions of the tent in which the design is embodied that are not considered part of the claimed design.
